United States Patent Office.

ERASTUS H. CLARK, OF APPLETON, WISCONSIN.

Letters Patent No. 92,514, dated July 13, 1869.

IMPROVEMENT IN SAW-BUCK.

The Schedule referred to in these Letters Patent and making part of the same.

To all whom it may concern:

Be it known that I, ERASTUS H. CLARK, of Appleton, in the county of Outagamie, and State of Wisconsin, have invented a new and useful Improvement in Saw-Bucks; and I do hereby declare that the following is a full, clear, and exact description thereof, which will enable others skilled in the art to make and use the same, reference being had to the accompanying drawings, forming part of this specification.

This invention relates to a new and useful improvement in saw-“bucks” or saw-“horses,” and

It consists in the construction and arrangement of parts, as will be hereinafter more fully described.

In the accompanying plate of drawings—

Figure 1 represents a sectional elevation of the saw-buck with the filing-clamps attached, as when filing the saw, the section being through the line *xx* of fig. 2.

Figure 2 is a top view of the same.

Similar letters of reference indicate corresponding parts.

A represents the ordinary saw-buck, with the addition of the serrated plate B, upon one of the sides of the “buck,” as seen in the drawing.

C represents lever-jaws, pivoted to the brace D, which brace is firmly attached to the buck, filling, or nearly filling the outer angles of one side.

E represents the pivots, which form the fulcrum of the lever-jaws.

The arrangement of the fulcrum of the lever-jaw, allows a freer action and more leverage than when the cross-round is made the fulcrum.

The two jaws C are pivoted to the inner sides of the buck, and are connected together at their lower ends, by the foot-piece or treadle F.

Each of the jaws is provided with a serrated plate,

the same as B, and it will be seen that the teeth are hooking downward, so as to prevent any upward movement of the stick of wood when being sawed.

G and H represent the clamps for filing the saw. In length they correspond with the distance between the parts of the saw-frame, so that the saw may be placed in the clamps without being taken from its frame.

The clamp H is supported by dowel-pins in the buck, and is triangular in form.

The clamp H is also supported and kept in place by dowel-pins, and is pressed against the saw by bearing on the foot-piece F.

The saw (in blue color) is seen between the clamps, and is marked I.

The clamps, being held or attached by loose dowels or steady-pins, are readily put in place for filing the saw, and detached and laid aside when not in use.

It will be seen that the top side of the broad clamp G is marked off, by parallel lines, at the proper angle with the edge of the clamp, to give the right bevel or “shear” to the teeth of the saw, when the file is held parallel therewith, thus enabling inexperienced hands to hold the file in the proper position in filing.

Having thus described my invention,

I claim as new, and desire to secure by Letters Patent—

The saw-buck A, when provided with the jaw C and clamps G H, all the parts being constructed, arranged, and operating substantially as and for the purposes described.

ERASTUS H. CLARK.
